BEET FLUME CONTROL MECHANISM

Gustave J. Daley, Stockton, Calif., assignor, by
mesne assignments, to The Stearns-Roger
Manufacturing Company, Denver, Colo., a cor-
poration of Colorado

Application December 13, 1937, Serial No. 179,540

13 Claims. (Cl. 302—14)

This invention relates to devices to control the movement of objects that are being flumed in a trench or ditch, and particularly to a device developed to control the movement of sugar beets which are being flumed in water to the factory.

After the beets are transferred from the farm to the sugar factory site it is customary to store them in bins or piles, commonly called beet sheds, from which they are flumed into the factory proper, at a rate that will supply the normal demand of the plant. Heretofore it has been the general practice to control the flow of beets by the use of a finger type gate. This gate lowers into the flume, retaining the beets but allowing the water to run through until such a time as more beets are needed. Then the gate is raised, allowing the beets to pass through.

This method has proven unsatisfactory in many cases, due to the intermittent starting and stopping of the flow of beets, and the accompanying uneven volume of feed.

The main object of this invention is to provide a flow control device so arranged that a close regulation of the quantity of beets being flumed to the factory can be obtained, as well as a continuous even flow of the beets irrespective of the volume or quantity thereof being passed through the control device.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Figure 1 is a sectional elevation of the control device installed in a flume.

Figure 2 is a sectional plan on line 2—2 of Fig. 1.

Referring now more particularly to the characters of reference on the drawings, the flume 1, here shown as being made of concrete, is formed at a suitable point in its length with opposed lateral bays 2 of substantially semi-circular form, the centers of curvature being outwardly of the plane of the sides of the flume proper.

Turnably mounted in the bays centrally of the curvature of the bays are vertical shafts 3, journaled at the bottom of the flume-bays in bearings 4 mounted in the concrete and at the top of the flume in bearings 5 supported on a suitable frame structure 6 resting on the flume and a portion of which overhangs the flume and bays.

A plurality of radial arms 7, 90° apart about the shafts, are arranged in vertically spaced sets thereon, the circular paths of their tips approaching close to each other centrally of the width of the flume. The arms on the two shafts, while on the same level, are disposed in staggered or intermediate relation to each other horizontally or so that they follow each other substantially 45° apart.

The shafts are rotated at the same speed but 10 in opposite directions and so as to maintain the above relation of the arms constant, by means of bevel gears 8 on the shafts above the bearings 5. These are engaged by bevel pinions 9 fixed on a horizontal shaft 10 journaled on the frame 15 structure. The shaft 10 is driven at an adjustable speed by an electric motor and reduction gearing unit 11 of common character mounted on an auxiliary frame 12 upstanding from the frame structure 6. The direction of rotation of 20 the shafts is such that the arms 7 as they turn into the water flowing along the flume, move in the direction of the flow.

Stationary clean out and deflector bars 13 are disposed between the arms of the two shafts, being provided with collars 14 surrounding the shafts. The bars extend downstream to the adjacent junctions of the walls of the flume proper with those of the bays, where the bars are formed with or secured to vertical strips 15 engaging 30 grooved supports 16 secured at said junctions.

In operation, as the beets in the flume, moving along with the water flowing therethrough, reach the rotating arms, they are received between adjacent arms on the two shafts, which form in effect turnstiles, and pass the beets through in controlled order, and in a definite and constant volume, regardless of the volume of beets in the flume ahead. The beets after passing by the arms cannot possibly be drawn and carried around the 40 bays owing to the bars 13, the vertical spacing of which is less than the diameter of any beet, as is the spacing of the arms themselves. The volume of beets passing the control mechanism at any time—and as the requirements of the factory 45 may necessitate—may be instantly altered by altering the speed of the drive unit, without altering the evenness of the flow of the beets.

At times a large quantity of beets may be held back behind the control device, thus forming a 50 sort of dam with a possibility of the water and beets overflowing the flume. To avoid this, a grating 17 is mounted in the flume below the top thereof and ahead of the control mechanism. This prevents the beets from rising to the top 55

of the flume, and only allows the water to do so.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. In combination, a flume to carry a flow of water and objects in and moved along by the water, and a driven turnstile structure mounted in the flume and arranged to allow of an unrestricted flow of the water but restricting the movement of the objects to an extent determined by the speed of the turnstile structure.

2. In combination, a flume to carry a flow of water and objects in and moved along by the water, and a driven turnstile structure mounted in the flume, and including a pair of vertical transversely spaced shafts, sets of radial arms projecting from the shafts, the arms on the two shafts being arranged in predetermined relation to each other and being spaced apart vertically a distance less than the thickness of an object in the water, and means to rotate the shafts in opposite directions and at the same speed.

3. In combination, a flume to carry a flow of water and objects in and moved along by the water, and a driven turnstile structure mounted in the flume, and including a pair of vertical transversely spaced shafts, vertically spaced sets of radial arms projecting from the shafts in evenly spaced relation circumferentially, the paths of rotation of the outer ends of the arms approaching close to each other, and means to rotate the shafts in opposite directions and at the same speed; the arms on the two shafts being arranged relative to each other so that when turning toward each other they are disposed in staggered relationship.

4. In combination, a flume formed with a bay in one side, a vertical shaft mounted in connection with the flume adjacent the plane of said one side thereof and substantially centrally of the width of the bay, a plurality of vertically spaced sets of radial arms projecting from the shaft, and of a length such that the path of rotation of their outer ends extends a predetermined distance toward the plane of the opposite side of the flume, and means to rotate the shaft in a direction to cause the arms, when turning into the flume, to move in the direction of flow along the flume.

5. A structure as in claim 4, with fixed diverter bars extending from the shaft between the arms to the side wall of the flume at the downstream junction thereof with the wall of the bay.

6. In combination, a flume formed with a pair of opposed bays in its sides, a pair of vertical shafts mounted substantially central of the width

of the bays and outwardly of the plane of the sides of the flume, vertically spaced sets of evenly spaced arms radiating from the shafts, the circular path of the outer ends of the arms closely approaching each other, bevel gears on the shafts above the arms, bevel pinions engaging the gears, and a drive shaft on which the pinions are mounted, said pinions being arranged to cause the shafts to rotate in opposite directions but at the same speed and the arms on the two shafts being disposed so as to turn past each other in a predetermined staggered relationship.

7. In combination, a flume formed with a pair of opposed bays in its sides, a pair of vertical shafts mounted substantially central of the width of the bays and outwardly of the plane of the sides of the flume, vertically spaced sets of evenly spaced arms radiating from the shafts, the circular path of the outer ends of the arms closely approaching each other, means to rotate the shafts in opposite directions but at the same speed and maintaining the arms on the two shafts in a constant relationship to each other and so that said arms when turning past each other in the flume are symmetrically staggered.

8. A structure as in claim 7, with stationary bars disposed in horizontal planes between the sets of arms and extending from adjacent the shafts to the corresponding sides of the flume at the downstream end of the bays.

9. A structure as in claim 1, with grate bars mounted across the flume below the top thereof and ahead of the turnstile structure.

10. In combination, a flume to carry a stream of water, and a rotary element inclusive of a shaft and radially projecting arms affixed thereto, in the stream of water and arranged to allow flow of the water but restricting the movement of solids carried by the stream of water, according to the speed of the element.

11. In combination, a flume to carry a stream of water, and a rotary element inclusive of a shaft and radially projecting rigid arms affixed thereto, said arms projecting in the stream of water and arranged to allow the flow of the water but restricting the movement of solids carried by the stream of water, according to the speed of the element.

12. In combination, a flume to carry a stream of water, and a driven element comprising a rotary shaft and arms mounted on the shaft and arranged to rotate conjointly therewith and to move through the stream of water in a position to allow flow of the water but restricting the movement of solids carried by the water, and variable speed mechanism for moving the driven element at selective velocities.

13. In combination, a flume to carry a stream of water, a rotary shaft having arms mounted thereon and spaced in the direction of their axis of rotation and projecting in the stream of water and arranged to allow flow of the water but restricting the movement of solids carried by the stream of water, according to the speed of the element, and stationary bars between the planes of movement of the rotary arms.

GUSTAVE J. DALEY.
